UNITED STATES PATENT OFFICE

2,410,565

ENGINE

James B. Brockhurst, Red Bank, N. J.

Application January 26, 1943, Serial No. 473,605

8 Claims. (Cl. 60—11)

1

This invention relates to internal combustion engines and my improvement is directed particularly to the provision of means whereby the piston power stroke, besides communicating an impulse axially to the crank-shaft through expansion of the compressed gaseous charge, at the same time also communicates further power impulse to the crank-shaft by turbine-like means that rotates the piston during its axial stroke, and gear means intermediate the piston and crank-shaft.

The power of an internal combustion engine may be increased in the above indicated manner in relation to the cylinder displacement, fuel consumption, unit of weight and front area of the engine, in an engine of given size and weight.

Accordingly, the piston may be divided into two superimposed halves, the top half being adapted to rotate upon its vertical axis and drive a connecting-rod geared to the crank-pin, whereby power is delivered to the crank-pin through a gear or perpetual lever having full leverage value throughout the entire 180° of the power stroke to turn the simple lever of the crank-throw and compound the leverage for turning the crank-shaft, and a bottom half of the piston adapted to receive the top end of a tubular connecting-rod adapted for driving the crank-shaft through a simple lever of the crank-throw in the usual manner and for housing the inner rotating connecting-rod.

The top end of the tubular connecting-rod is U-shaped to provide oppositely disposed wrist-pin arms adapted for pivotal engagement with the bottom half of the piston and for the further accommodation of a universal joint carried by the rotating inner connecting-rod to provide concentric pivotal movement with respect to the top end of the said two connecting rods.

The cylindrical face of the top half of the piston is fluted tangentially around the entire circumference to provide vanes at the said face and the flutings extend obliquely downward from the top edge to substantially midway of the upper piston part to an annular opening communicating with an interior chamber adapted in cubic area to accommodate the entire volume of engine charge when such charge is compressed within the said chamber. When the piston is placed in position in the cylinder the said flutings provide passageways between the outer surface of the

2

piston and the inner surface of the cylinder extending from the piston chamber to the cylinder chamber.

Other features and advantages of my invention will hereinafter appear.

5 In the drawings:

Figure 1 is a front sectional view of a cylinder with its piston and master connecting rod as part of a nine cylinder, air cooled engine.

10 Fig. 2 is a side sectional view of the same.

Fig. 3 is a section on the line 3—3 of Fig. 2.

Fig. 1A is a front sectional view of a liquid cooled cylinder including a modified form of piston capable of both rotary and axial movement, 15 the piston in this view being at the end of its expansion stroke.

Fig. 2A is a side sectional view of the cylinder of Fig. 1A, with the piston at the end of its compression stroke.

20 Fig. 3A is a section on the line 3A—3A of Fig. 2A, and

Fig. 4A is a detail side view showing one half of the fixed sleeve that ensheathes the connecting-rod.

25 In Figures 1 to 3 let 1 indicate a cylinder forming part of a nine-cylinder air-cooled engine, only parts of certain remaining cylinders being illustrated in Fig. 1. The piston for said cylinder is shown to be in two parts, whereof the lower 30 part is indicated by the numeral 2 and its upper part by the numeral 3, said upper part carrying piston rings 3a.

The lower piston part 2 is adapted to be reciprocated in the cylinder in the usual manner, and 35 is provided with bearings 4 in which wrist-pin arms 5 are able to rock, said arms being carried by a U-shaped portion 6 from which a tubular connecting-rod 7 extends, said rod being enlarged at its lower portion 8 for a purpose to be described 40 hereinafter and at said lower portion forming a bearing for the crank-pin 9.

The terms upper and lower piston parts are used here only to conveniently describe these 45 elements as they appear in the drawings of the fully illustrated cylinder forming part of the complete engine.

The upper piston part 3, which is separate from the lower part 2, as at x and is adapted to rotate, is hollow to provide a chamber 10 and is 50 divided by an annular gap or slot 11, the divi-

sional units being connected as by a screw stud 12 that is threaded into centrally disposed concentric webs 13 in the respective units, the connection being integrated by means of welding material 14 placed on top of stud 12 within the upper web 13 to weld said stud and webs together.

Stud 12 at its lower end is secured to a yoke 15 that forms part of a universal joint, with which is engaged the upper end of a connecting-rod 16 that is housed within the tubular connecting-rod 1.

Connecting-rod 16 is provided at its lower end with a bevel gear 17 that meshes with a bevel gear 18 on a shaft 19 which carries at one end a pinion 20 that meshes with a gear 21 carried by the crank-pin 9. The gears 17 and 18 are housed within the hollow portion 8 of tubular connecting-rod 1.

Obviously rotation of upper piston portion 3 will be communicated, through connecting-rod 16, bevel gears 17 and 18, pinion 20 and gear 21 to the crank-shaft 22 through crank-pin 9.

Power to rotate the upper piston part 3 is provided by means for introducing a charge of atmospheric air into the cylinder chamber 10a, compressing said charge into chamber 10, injecting fuel into the charge as through an orifice 23 in the cylinder wall when aligned with slot 11 at the point of maximum compression, and then by impingement of the expanded charge upon angular vanes or flutes 24 formed in the outer peripheral wall of the upper divisional unit of piston part 3. It was of course through these flutes 24 that atmospheric air had entered chamber 10 during the compression stroke after passing through the single valve 25 in its valve-open position (see Fig. 2), into the cylinder during the down or suction stroke of the piston.

The air is so greatly compressed into the piston chamber by the piston moving upwardly in the cylinder that it reaches a temperature of 1000° F. Just before the piston reaches upper dead centre fuel oil is sprayed into the piston chamber 10 and spontaneously ignited. Power of this explosion is passed to the crank-shaft in the following three ways, substantially simultaneously:

1. Through a charge of high velocity escaping from the piston chamber into the cylinder impinging upon the oblique vanes of the piston to rotate the same upon its vertical axis.

2. Through the reactive force exerted downward at the periphery of the piston by its recoil in starting the expanded charge moving through the flutes upward at high velocity to rotate the piston upon its vertical axis.

3. Through a charge of high compression in the cylinder projecting the piston outwardly in the usual well-known manner of a simple reciprocating engine.

As more heat units of a given displacement are converted into mechanical energy in an engine of the present type than in a simple engine, the products of combustion are necessarily cooler and less expansive when exhausted into the atmosphere and therefore an engine of the former type is much quieter than an engine of the latter type, which is desirable in war time aviation.

Now referring to the form of my invention illustrated in Figures 1A to 4A the cylinder 26 is shown as jacketed at 27 and provided with the single valve 28. The piston in this form is in one piece, having an upper portion that comprises a chamber 29, bounded by the piston head 30, wall 31 and base 32, said base separating

chamber 29 from the skirt 33, which latter carries the piston rings 34. The upper piston portion is reinforced by a central web 35 that extends between and connects head 30 and base 32. Chamber 28, becomes filled with air during the piston compression stroke through flutes 36 in the piston periphery, as in the structure of Figs. 1 and 2, which air becomes compressed during the piston compression stroke, and an orifice 37 in the cylinder wall, in alignment with a circumferential slot 38 in the piston wall at the point of maximum compression, permits the injection of liquid fuel for ignition and expansion of the charge.

The resulting forces of expansion combine to rotate the piston and drive it axially.

A fundamental difference between this form of my invention and that shown in Figs. 1 to 3 is that here the piston is in a single piece and it has a single connecting-rod 39 that extends between a universal joint 40 carried by base 32 and a bevel gear 41, which latter is in mesh with a bevel gear 42 that is formed on the crank-pin 43, by which means both the rotating and the reciprocating movements of the piston are communicated to the crank-shaft.

A sleeve 44, that is made in two parts, envelopes connecting-rod 39, said two parts being united as by bolts 45, the cup-shaped upper part 46 of said sleeve containing stepped bearing material 47 for co-operation with the correspondingly stepped formation of said connecting-rod at its upper portion. The connecting-rod, at its lower end is provided with a two-part, connected shell 48 that revolvably embraces the crank-pin, said sleeve serving as a guide for the connecting-rod.

While I have herein described and illustrated my invention of combined rotating and reciprocating piston in its application to an internal combustion engine, it may obviously be equally well employed in the operation of a steam-engine.

Variations within the spirit and scope of my invention are equally comprehended by the foregoing disclosure.

I claim:

1. In an engine, a cylinder, a piston having an internal chamber of fixed cubical capacity and a crank shaft, means for the introduction of a power medium into said internal chamber, means whereby expansive power introduced within said chamber operates directly to both project and rotate said piston, and respective means for simultaneously applying both the projecting and rotating piston movements to the rotation of the crank shaft.

2. In an internal combustion engine, a cylinder, a piston having an internal chamber of fixed cubical capacity and a crank shaft, separate means for the introduction of power media into said internal chamber, means whereby expansive power generated within said chamber operates directly to both project and rotate said piston, and respective means for simultaneously applying both the projecting and rotating piston movements to the rotation of the crank shaft.

3. In an internal combustion engine, a cylinder, inlet and exhaust means for said cylinder, a piston and a crank shaft, said piston provided with an interior chamber, and angular flutes, forming vanes which provide intermediate passageways around the piston, said passageways connecting the cylinder space above the piston with said piston chamber and serving to admit air into said

chamber during the compression stroke, means for injecting fuel into said chamber whereby combustion and expansion of the products of combustion, acting on the vanes, serve to rotate said piston, a connecting rod and gear means between the piston and crank shaft co-acting with the piston in its reciprocating and rotating movements to rotate the crank shaft.

4. In an internal combustion engine, a cylinder, inlet and exhaust means for said cylinder, a piston and a crank shaft, said piston provided with an interior chamber, and angular flutes, forming vanes which provide intermediate passageways around the piston, said passageways connecting the cylinder space above the piston with said piston chamber and serving to admit air into said chamber during the compression stroke, means for injecting fuel into said chamber whereby combustion and expansion of the products of combustion, acting on the vanes, serve to rotate said piston, a connecting rod, a crank pin, and gear means respectively on said connecting rod and crank pin, whereby the combined rotative and axial movements of said piston are communicated to said crank shaft.

5. In an internal combustion engine, a cylinder, inlet and exhaust means for said cylinder, a piston, a crank shaft, a crank pin therefor, said piston provided with an interior chamber, and angular flutes, forming vanes which provide intermediate passageways around said piston, said passageways connecting the cylinder space above the piston with said piston chamber and serving to admit air into said chamber during the compression stroke, means for injecting fuel into said chamber whereby combustion and expansion of the products of combustion, acting on the vanes, serve to rotate said piston, a connecting rod and gear means between the piston and crank shaft co-acting with the piston in its reciprocating and rotating movements to rotate the crank shaft and a guide sleeve embracing said connecting rod, said sleeve having a shell that revolvably embraces said crank pin.

6. In an internal combustion engine, a cylinder, inlet and exhaust means for said cylinder, a crank shaft, a piston provided with an interior chamber, and means for admitting fuel and air into said interior chamber during the compression stroke including means for injecting fuel through

the cylinder wall before the end of the compression stroke and helical vanes on the upper part of said piston providing intermediate passageways connecting the cylinder space above the piston with said piston chamber, whereby combustion and expansion of the resulting products of combustion, acting on the vanes, serve to rotate said piston, a connecting rod and gear means between the piston and crank shaft coacting with the piston in its reciprocating and rotating movements to rotate the crank shaft.

7. In an internal combustion engine, a cylinder, inlet and exhaust means for said cylinder, a crank shaft, a piston provided with an interior chamber, and means for admitting fuel and air into said interior chamber during the compression stroke including means for injecting fuel through the cylinder wall before the end of the compression stroke and helical vanes on the upper part of said piston providing intermediate passageways connecting the cylinder space above the piston with said piston chamber, whereby combustion and expansion of the resulting products of combustion, acting on the vanes, serve to rotate said piston, a connecting rod and gear means between the piston and crank shaft coacting with the piston in its reciprocating and rotating movements to rotate the crank shaft, and a guide sleeve embracing said connecting rod, said sleeve having a shell that revolvably embraces said crank pin.

8. In an internal combustion engine, a cylinder, an air inlet and exhaust gas means for said cylinder, a crank shaft, a piston provided with an interior chamber, means for forming a hydrocarbon charge in said chamber during the compression stroke including helical vanes providing intermediate passageways connecting the cylinder space above the piston with the piston chamber, whereby combustion and expansion of the products of combustion during the working stroke, acting on the vanes, serve to rotate said piston, and means actuated by the piston in its reciprocating and rotating movements to rotate the crank shaft including a connecting rod and gear means between the piston and the crank shaft acting together on the crank shaft to rotate the same.

JAMES B. BROCKHURST.
